Property Law, LLP(57) **CLAIM**

We claim the ornamental design for shelf components, as shown and described.

DESCRIPTION

FIG. 1 is a perspective view of shelf components in accordance with our new design; and,
FIG. 2 is a top view thereof.

Portions of the shelf components outside of the boundary lines (shown as dot-dash broken lines) are shown in broken lines to illustrate unclaimed environmental subject matter that forms no part of the claimed design. Additionally, portions of the design within the boundary lines are also shown in broken lines to indicate unclaimed environmental subject matter forming no portion of the claimed design. Two sets of break lines bisect individual product channels of the tray to indicate that the overall width of each channel of the tray and/or spacing of the wings of the tray are not part of the claimed design.
